UNITED STATES PATENT OFFICE.

WILLIS A. TRECOTT, OF FAIRPORT, NEW YORK.

SEPARATING-MACHINE.

No. 880,603.

Specification of Letters Patent.

Patented March 3, 1908.

Application filed April 20, 1907. Serial No. 369,249.

To all whom it may concern:

Be it known that I, WILLIS A. TRECOTT, of Fairport, in the county of Monroe and State of New York, have invented certain new and useful Improvements in Separating-Machines; and I do hereby declare the following to be a full, clear, and exact description of the same, reference being had to the accompanying drawings, forming a part of the specification, and to the reference-numerals marked thereon.

This invention relates to separating machines for vegetables, fruit and the like, such as potatoes, oranges and apples, and particularly to that type of separating machines in which the smaller articles are caused to pass through openings in a separating element.

An object of my invention is to provide a separating element which will have a maximum number of openings through which the smaller articles may pass, whereby a better separation will be secured without subjecting the articles to so much agitation which causes them to become bruised.

Another object is to provide a movable agitator driven by the separating element to dispense with unnecessary driving parts and to prevent the articles being subjected to sudden, sharp blows common to stationary or independently driven agitators.

Still another object is to provide a chute so constructed that it will be inexpensive to manufacture and will separate dirt and other extraneous matter from the articles.

A further object is to provide a hopper which, while preventing the discharge of the articles through one wall thereof, will yield and permit any articles, held by the belt, to pass by said wall.

A still further feature is the provision of a driving means which may be under the full control of the operator and will permit his supervision of the material on the separating belt.

To these and other ends the invention consists of the parts and the combinations of parts shown in the accompanying drawings, hereinafter described and more particularly pointed out in the appended claims.

In the drawings: Figure 1 is a top view of my invention; Fig. 2 is a transverse vertical section; Fig. 3 is a side elevation of the machine, parts being shown in section; Fig. 4 is a detail sectional view of the intermittent

driving connection; Fig. 5 is a plan view of one of the rings of the separating element, and Fig. 6 is a sectional view showing the manner of spacing the rings.

Similar reference numerals in the several figures indicate similar parts.

With more particular reference to the drawings A indicates a frame which in the present instance comprises four uprights 1 suitably connected together at their upper ends by two longitudinal members 2 and a number of cross pieces 3. Supported on the upper part of the frame is a separating element B which preferably is in the form of an endless belt and which comprises a plurality of parallel rows of rings 4 and means, as for instance, links 5, spacing said rings at such distances that the spaces formed between every four rings will have a width approximately equal to the diameter of the space enclosed by each ring.

To prevent the ends of the links 5 injuring the articles to be separated or interfering with their passage through the ring spaces, and also to prevent the links sliding on the rings and thus destroying the spaced relation of the latter, the rings are each provided with a plurality of eyes 6 in which the ends of the links 5 are secured. When the separating element is in the form of an endless belt, as shown in the present instance, certain of the links are left open, as at 5^a, so that by removing these links the belt may be removed from the machine. The endless belt is supported by a pair of horizontally arranged rollers 7 and 8 journaled on the frame A at opposite ends thereof and carrying frusto-conical projections 9 which enter the spaces of the separator belt to drive the latter.

The mechanism for driving the belt is under the full control of the operator and preferably comprises two treadles 10 and 11 arranged one on each side of the machine, extending longitudinally of the latter, and having a common pivot 12. To hold the treadles in elevated positions two swing levers 13 and 14 are arranged one at each end of the frame, are pivoted to one side of the latter, and move in guides 15 on side faces of uprights on the other side of the frame. The free ends of the levers 13 and 14 are bent laterally, at 16, about the uprights and have the lower ends of coil springs 17 secured thereto,

the upper ends of the springs being secured at 17°, to the adjacent uprights so as to hold the levers 13 and 14 in elevated positions. Both of the treadles are connected to the levers 13 and 14 as by links 18, pivoted to the levers and to the treadles and arranged in pairs, each pair being at opposite ends of the frame. It is apparent that the depression of either treadle will cause the depression of the other, thus enabling the machine to be operated from either side. The treadles are connected to one of the rollers, in this instance to roller 7, by an intermittent driving connection, preferably in the form of a strap 19 having one end secured at 20 to one of the treadles and its other end secured to and passing about a drum 21. Drum 21 turns on the shaft of the roller and carries a pawl 22 which, when the drum is rotated in one direction by the depression of the treadles, engages the teeth on a toothed wheel or ratchet 23 rigidly secured to the roller shaft, and causes the rotation of the roller 7 and the movement of the belt B. The drum is rotated in the other direction by a helical spring 24 surrounding the shaft of roller 7 and secured at one end to the drum 21 and at its other end to a flanged bearing 25 in which the shaft turns.

30 The articles to be separated are fed onto the belt at one end of the latter and are prevented from moving off the belt, either at this end or at the sides, by a hopper 26 open at one end and side boards 27 extending 35 along the sides of the belt from the open end of the hopper. The smaller articles drop through the upper portion of the separating belt B onto a receptacle arranged below this portion of the belt. This receptacle is preferably in the form of a chute to discharge the material to one side of the machine. As a preferred and novel form of chute C, I employ a plurality of curved slats 28 arranged transversely to the incline of the chute, the 45 curvature of the slats gradually increasing from one side of the machine to the other. The slats are preferably connected by cross strips 29 and are secured at their ends to the two end cross pieces 3 which, for this purpose, are beveled so that the ends of the slats 50 may lie properly. The slats are preferably spaced to permit the discharge of dirt and other extraneous matter.

From the hopper 26 the larger articles are 55 carried by the belt to the open end of the machine, where they are discharged into any suitable receptacle. In moving to the discharge end, the articles on the belt pass successively over movable agitators in the form 60 of rollers 30 formed with rows of frusto-conical projections 31 which are adapted to pass through successive rows of the rings and thus to be carried along by the belt. These projections 31, together with the roll surface,

cause the displacement of any articles in the 65 openings of the belt, and this displacement takes place so gradually that the articles are not bruised.

In some instances the articles will become 70 jammed in the belt openings and will be carried again to the feeding end of the machine, and, as the hopper must be closed at this end to prevent the escape of the articles, some 75 means must be provided to permit the articles to move past the hopper wall with the belt, as, otherwise, the articles would engage said wall and cause damage to the delicate belt or to other parts of the machine. To 80 overcome this difficulty I construct the hopper with a yielding wall preferably in the form of a door 32 hinged at 33 so as to swing in the direction of movement of the belt, but not in the opposite direction, thus preventing the outlet of the articles except through the open end of the hopper.

85 The machine forming the subject matter of this invention may be manufactured and sold very cheaply. In operation it is simple and effective, being adapted for control by one person who not only furnishes its motive power, but can supervise all of the articles being separated.

I claim as my invention:

1. In a separating machine, a separating element comprising a plurality of rings, and means spacing said rings at such a distance that the spaces formed by every four rings will have a width approximately equal to the diameter of the space inclosed by each ring.

2. In a separating machine, a separating element comprising a plurality of rings each having a plurality of eyes, arranged about the same, and links, each secured in the eyes of two rings and holding said rings in spaced relation.

105 3. In a separating machine, a frame having a hopper and a discharge end, and a separating element extending from the hopper to the discharge and comprising a plurality of rings and means spacing said rings at such a distance that the spaces formed by every four rings will have a width approximately equal to the space inclosed by each ring.

110 4. In a separating machine, an endless belt comprising a plurality of rings and links holding the rings in spaced relation, means for moving the belt and a chute arranged beneath a portion of the belt to receive material separated by the belt and discharge said material to one side of the belt.

115 5. In a separating machine, a separating element comprising an endless belt formed of a plurality of rings, and means spacing said rings at such a distance that the spaces formed between every four rings will have a 120 width approximately equal to the diameter of the space inclosed by each ring, and means for moving said belt.

6. In a separating machine, the combination with an endless separating belt and means for moving the belt, of an agitator mounted independently of the belt, engaged and moved by the latter and having portions adapted to engage and displace articles on the said belt.

7. In a separating machine, an endless separating belt having separating openings, means for moving the belt, and a movable agitator having projections entering the openings and to displace articles therefrom and engaged by the belt to drive the agitator.

8. In a separating machine, an endless separating belt having separating openings, means for moving the belt, and a roller driven by engagement with the belt and arranged beneath the openings in a portion of the belt to displace articles within the openings.

9. In a separating machine, an endless separating belt having separating openings, means for moving the belt, and an agitating roller arranged below a portion of the belt and having projections entering the separa-

ting openings and engaged by the belt to drive the roller.

10. In a separating machine, a separating element, and a chute formed of a plurality of slats of gradually increasing curvature, and arranged to receive material from the separating element.

11. In a separating machine, a separating element, and a chute positioned to receive material from the separating element and formed of a plurality of curved slats arranged transversely to the incline of the chute.

12. In a separating machine, an endless separating belt, and means for driving the belt comprising a pair of treadles arranged at opposite sides of the belt, a common pivot for the treadles, a lever arranged above the treadles, a pair of links connecting the treadles with the lever, a spring for holding the lever elevated, and connection between the treadles and the belt.

WILLIS A. TRECOTT.
